DRIVE FOR MULTICOLOR PRESSES

Charles W. Harrold, University Heights, Ohio, assignor to Harris-Seybold-Potter Company, Cleveland, Ohio, a corporation of Delaware

Application January 4, 1936, Serial No. 57,542

19 Claims. (Cl. 101—177)

This invention relates to improvements in drive for multicolor presses. It is to be understood, however, that the invention is applicable to other sheet handling machines wherever it is of importance to preserve accurate register of the sheets while different operations are being performed upon them.

The usual method of driving a multicolor press having a series of printing and sheet carrying or transfer cylinders is by means of gears carried by each of the cylinders and forming an intermeshing train. Power is supplied to one of the gears and transmitted through the train to the other cylinders. In this type of drive the sheet carrying cylinders because of the stresses incident to the transmission of power suffer deflections which vary with the load being transmitted, and hence with the speed at which the press is operated. It may be seen therefore that registration between successive printings on a sheet would tend to vary according to the speed at which the sheet is printed.

The principal object of the invention is the provision of a drive such that deflection, back lash and wear in the various driving members will not affect the proper registering of successive printings upon the sheet.

Another object is to lessen the load on certain of the gears of a multicolor press or the like, by imparting driving force to the press at more than one point in the gear train.

Another object is the provision of means whereby when two non-adjacent gears of a train are driven from the same source of power independently, there will be no tendency of the intermediate gears to bind, and at the same time there will be accurate positioning of these gears with relation to each other at predetermined points in their rotation.

Still another object of the invention is to substantially relieve the transfer mechanism of driving load, so that any tendency to assume an out-of-register relation under high speed operation of the press is minimized.

Other objects and features of novelty will appear as I proceed with the description of those embodiments of the invention which, for the purposes of the present application, I have illustrated in the accompanying drawings, in which—

Fig. 1 is a more or less diagrammatic side elevational view of a multicolor off-set printing press embodying the invention.

Fig. 2 is a fragmental end elevation of the same.

Fig. 3 is a view similar to Fig. 1 showing a somewhat different application of the invention.

Fig. 4 is an end view of the construction shown in Fig. 3.

Fig. 5 is a detail view showing the gear elements on a transfer cylinder which may be employed in connection with the invention, the cylinder being in a position where a sheet is being transferred thereto from a cooperating cylinder.

Fig. 6 is a similar view of the same parts after a further rotation of 90°.

Fig. 7 is an end elevation of the gear units of Figs. 5 and 6, and

Fig. 8 is a detail view on a larger scale showing the angular displacement between the gear elements when the transfer cylinder is in the position of Fig. 6.

Referring to the drawings, Fig. 1 represents a three color off-set printing press wherein there are three printing units 10, 11 and 12, each comprising a plate cylinder 13, a blanket cylinder 14 and an impression cylinder 15. These cylinders are mounted in any conventional manner, and upon each of the shafts upon which they are carried there is a drive gear indicated in the drawing as 13', 14' and 15', respectively. The three cylinders of each unit are therefore geared together in the usual manner.

A motor 16 is employed to drive through a multiple belt 17 or other suitable driving element, a pulley 18 keyed to one end of a drive shaft 19 arranged longitudinally of the press. This shaft has bevel gears 20, 21 and 22 fixed thereupon, one for each printing unit. These gears mesh with other bevel gears 23, 24 and 25 keyed respectively to the shaft of each unit upon which the impression cylinder 15 of that unit is mounted. By this means each of the three printing units is driven directly from shaft 19 independently of each of the other units, that is to say in no case does the drive for any given unit pass through the drive for any other unit.

There may be two, three or any greater number of printing units. Between successive units sheet transfer means is provided, which is operatively connected with both of the units on opposite sides thereof. One element of the transfer means is so constituted that at times it takes its driving force from the printing unit to the rear and at other times from the printing unit in advance. This specially constructed transfer element provides gear slack take-up means which is utilized to prevent any binding due to drive from opposite directions, and is also con-

structed to bring its sheet grippers into register first with the unit to the rear and then with the unit in advance, whereby there is no building up of any out-of-register tendency in the sheet transferring mechanism.

The sheet transfer mechanism between successive printing units in each instance comprises three cylinders or rolls 26, 27 and 28. Fixed with respect to roll 26 there is a gear 26' which meshes with gear 15' of one unit, while a gear 28' on roll 28 meshes with gear 15' of the next succeeding unit.

The driving mechanism for the intermediate roll 27 of the sheet transfer mechanism will now be described. On the shaft 29 of this roll there is loosely mounted a gear 30 of approximately half the thickness of gears 26' and 28'. The shaft and the gear are slightly eccentric with respect to each other. Preferably this is effected by making the hole in the gear hub eccentric. Directly in front of loose gear 30 there is an identical gear 31 which is provided with a shaft hole having the same eccentricity as that of gear 30. The gear 31 is keyed to shaft 29, as indicated at 32. In Figs. 5 and 6 the center of the shaft is marked 33 and the center of the gear 31 is marked 34.

Any suitable means may be provided for preventing relative longitudinal movement between the two gears 30 and 31. The means illustrated herein consists of screws 35 which extend through slots 36 in gear 31 into threaded openings in gear 30. Washers 37 beneath the heads of studs 35 overlie the slots.

Means are provided also tending to displace the two gears 30 and 31 angularly with respect to each other. In the illustrated case this means consists of a plurality of headed posts 38 which are threaded into tapped openings in gear 30, the heads of the posts projecting into pockets 39 in the rear side of gear 31. The head of each of the posts 38 has a smooth bore therethrough which slidably receives a pin 40. A coil spring 41 surrounds each pin 40, bearing at one end against the head of post 38 and at the other end against the head of the pin. The latter is rounded as shown at 42, and is received in a socket formed in the gear 31 at the end of pocket 39. It will be apparent therefore that the springs 41 tend to expand and produce slight rotation of gear 30 with respect to gear 31 and shaft 29. Such angular displacement is illustrated in Figs. 6 and 8.

The double gear 30, 31 meshes with gears 26' and 28' on opposite sides. The two meshing points are shown separated by 180° in Figs. 5 and 6 for convenience in illustration, but it should be understood that they may be at various angles, as the design of the machine may dictate. Sheet grippers 43 are mounted on the roll 27 in radial alignment with the point 34 of greatest eccentricity of gears 30 and 31. Hence when a sheet is received upon the roll 27 it is received at the point of greatest eccentricity of the gears for the roll, and when it is delivered from that roll it is delivered from the point of greatest eccentricity. At the position shown in Fig. 5 a sheet is at the point of being delivered from the roll 27 to the roll 28. At this time the two gears 30 and 31 have their high teeth, or teeth of greatest eccentricity, in engagement with the teeth of gear 28'. Hence there is close meshing of the gears 30 and 31 with the gear 28', and accurate registering of the roll 27 with the roll 28. This close meshing draws the loose gear 30 into perfect alignment with the gear 31 against the action of springs 41. When

the sheet has been delivered in this manner the high point of gears 30 and 31 turns in the direction of the arrow in Figs. 5 and 6 until the gears reach the position illustrated in Fig. 6. At this point the meshing of the gears 30 and 31, not only with the gear 28' but also with the gear 26', is rather loose, and consequently the springs 41 are free to act. They therefore displace the gear 31 with respect to the gear 30 as indicated in Fig. 6, taking up all slack and preventing undue noise. The next quarter revolution brings the high point of these gears into mesh with gear 26', when again the gears 30 and 31 are brought into alignment and the register between rolls 26 and 27 becomes accurate. At this point a sheet is received by roll 27 from roll 26. The next quarter revolution carries the gears to another position of loose register, where angular displacement takes up slack, and the final quarter revolution brings them again into the position of Fig. 5, completing the cycle.

The sheets to be printed enter the press from the feed table 44, pass through the press along the path indicated by arrows in Fig. 1, and out by way of a delivery cylinder 45 which is driven by a gear 45' meshing with gear 15' of the last printing unit.

While the transfer mechanism as herein described comprises three cylinders, it is to be understood that other means may be employed without departing from the broad aspects of my invention. For example, the transfer means may comprise a continuous conveyor having sheet gripping devices, or may comprise any other number of transfer cylinders of any suitable size.

When the transfer mechanism comprises a single moving element such as a cylinder or a continuous conveyor, that element carries means for registering its grippers first with the previous printing unit and next with the succeeding printing unit, whereas when more than one element is employed in the transfer mechanism the gripper registering means may be applied to any one of such elements.

Furthermore, while I employ an eccentric gear to assure accurate registration of the sheet at the time it is taken by the intermediate transfer cylinder and again when it is delivered to the succeeding cylinder, this desired result may be accomplished in other ways, as for example by the use of adjustably fixed or spring actuated register segments, or by other means known to those familiar with the art.

The modification illustrated in Figs. 3 and 4 differs in no respect from that of the preferred form illustrated in Figs. 1 and 2, except that the drive, instead of being communicated directly to one of the cylinders of each printing unit, is communicated to one of the cylinders of each transfer mechanism, while the eccentric gear is moved forward to the cylinder next in advance beyond that of Figs. 1 and 2, in order that it may be midway between the successive driven elements. Similarly, the drive could be transmitted to any one of the corresponding cylinders of the various printing units, as well as to any one of the elements of the transfer mechanism, although I prefer to transmit the drive to some cylinder of each printing unit and thereby to relieve the transfer mechanism of the load imposed by the driving of the printing cylinders.

In Figs. 3 and 4 the cylinders of the printing units and of the transfer mechanisms carry the same reference numerals as in Figs. 1 and 2, but the transfer cylinder 27 has attached thereto a

concentric gear 27' meshing with the gear 26' on cylinder 26, while cylinder 28 instead of having a fixed concentric gear is provided with the eccentric gears 30 and 31 mounted as previously described, these latter gears meshing with gear 27' of the transfer mechanism and gear 15' of the next printing unit.

Drive for the machine is furnished from a suitable source of power such as an electric motor 46 operating through a multiple belt 47 to drive a pulley 48 keyed to a shaft 49 extending longitudinally of the press. Upon this shaft are keyed at proper points bevel gears 50, 51 and 52. Gears 50 and 51 mesh with bevel gears 53 and 54 on cylinders 26 of successive transfer mechanisms, and bevel gear 52 meshes with a bevel gear 55 on delivery cylinder 45, the gear 45' of which communicates driving force to the last printing unit.

It will be observed that I have provided a drive which is carried directly to each printing unit independently of the transfer mechanism, thereby relieving the latter of the function of transmitting power to the printing units. In particular this drive is independent of the devices employed for securing accuracy of registration of a sheet as it is transferred from one unit to the next. At the same time, however, each transfer mechanism is operatively connected at its opposite ends to corresponding elements of the printing units between which the transfer mechanism is located. Because of the eccentric gears on a transfer cylinder positioned midway between the successive printing units, a sheet handled on that cylinder will be taken by grippers correctly registered with the preceding printing unit, and will be delivered to grippers accurately registered with the succeeding printing unit. In other words, there can be no accumulation of slack in the gears of the transfer mechanism. The drive from the two printing units meets in the two-part gear of the intermediate cylinder, and because of the loose meshing of that gear with the gears on opposite sides, there is no jamming of the gears, while the angular play between the elements 30 and 31 of the two-part gear serves to take up the slack during the movement of the point of greatest eccentricity from meshing relation with one gear to meshing relation with the other gear.

I have disclosed herein specifically means for producing accurate register by special formation of the gears attached to one of the transfer cylinders, that is by so forming the gear at the gripper point as to produce close meshing relation at that point. However, it is possible to produce accurate register of the grippers of a transfer cylinder with those of the preceding and succeeding cylinders, or accurate registration of the grippers of an endless conveyor with the grippers of preceding and succeeding elements, by means other than gear formation, and hence in certain broader aspects of the invention the particular means employed for accomplishing registration is of minor importance.

Having thus described my invention, I claim:

1. In a drive for a sheet handling machine having a plurality of units adapted to operate upon the sheets in registered relation, each of said units comprising a plurality of operating elements and adjacent units being operatively interconnected by means of said elements, means for imparting driving force to a single element in each unit from which the other elements of the units take their driving force, and means associated with said other elements for compensating

against the tendency to bind due to the application of driving force forwardly and rearwardly from said single elements.

2. In a drive for a sheet handling machine having a plurality of units adapted to operate upon the sheets in registered relation, each of said units comprising a plurality of operating elements and adjacent units being operatively interconnected by means of said elements, means for imparting driving force to a single element in each unit from which the other elements of the units take their driving force, one of said other elements in each unit comprising means for registering that element with the preceding element when it takes a sheet and registering it with the succeeding element when it delivers a sheet.

3. In a drive for a sheet handling machine having a plurality of units adapted to operate upon the sheets in registered relation, each of said units comprising a plurality of operating elements and adjacent units being operatively interconnected by means of said elements, means for imparting driving force to a single element in each unit from which the other elements of the units take their driving force, and means associated with one of the other elements in each unit for causing it to take driving force from the preceding element at the instant when it takes a sheet from the latter element and for causing it to take driving force from the element in advance at the instant when it delivers a sheet to that element.

4. In a drive for a sheet handling machine having a plurality of units adapted to operate on the sheets in registered relation, a plurality of transfer cylinders between successive units, the cylinders of each transfer cylinder group being geared together and to the said units on either side thereof, and driving connections for one of the transfer cylinders of each group such that driving force for that cylinder is taken alternately in each revolution from the driving element to the rear and the driving element in advance.

5. In a drive for a sheet handling machine having a plurality of units adapted to operate on the sheets in registered relation, a plurality of transfer cylinders between successive units, the cylinders of each transfer cylinder group being geared together and to the said units on either side thereof, the gear for one transfer cylinder of each group having a portion of its teeth more closely intermeshing with adjacent gears than the other portions thereof.

6. In a drive for a sheet handling machine having a plurality of units adapted to operate on the sheets in registered relation, a plurality of transfer cylinders between successive units, the cylinders of each transfer cylinder group being geared together and to the said units on either side thereof, the gear for one transfer cylinder of each group having a portion of its teeth extending further from the axis of rotation of the cylinder than the other portions thereof, and sheet grippers on said last named cylinder positioned substantially in a line with the high teeth of the gear for that cylinder.

7. In a drive for a sheet handling machine having a plurality of units adapted to operate on the sheets in registered relation, a plurality of transfer cylinders between successive units, the cylinders of each transfer cylinder group being geared together and to the said units on either side thereof, the gear for one transfer cylinder of each group being mounted slightly eccentric of

- the cylinder, whereby it meshes closely with adjacent gears on either side alternately during each revolution.
8. In a drive for a sheet handling machine having a plurality of units adapted to operate on the sheets in registered relation, a plurality of transfer cylinders between successive units, the cylinders of each transfer cylinder group being geared together and to the said units on either side thereof, the gear for one transfer cylinder of each group being mounted slightly eccentric of the cylinder, whereby it meshes closely with adjacent gears on either side alternately during each revolution, and sheet grippers on said last named cylinder positioned substantially in line with the point of maximum eccentricity of the gear for that cylinder.
9. In a rotary multicolor press having separate printing units each comprising a plurality of cylinders, one of which in each unit is an impression cylinder, gripper transfer means for transferring sheets from one impression cylinder to another, said means comprising a transfer cylinder connected with the impression cylinders on either side thereof by gearing possessing slack, and said gearing comprising means for registering said grippers alternately with the grippers of the preceding and succeeding impression cylinders.
10. In a multicolor press having separate printing units, means for driving each unit independently of the others, sheet gripping means forming a part of each unit, and means for transferring sheets from one unit to another comprising grippers arranged to take a sheet from the gripping means associated with one unit and to deliver said sheet to the gripping means associated with the next adjacent unit.
11. In a rotary printing press, a plurality of interconnected sheet carrying members, sheet gripping means on said members, and driving means for said members arranged to impart driving force to two of the members independently of each other.
12. In a multicolor press having separate printing units each of which includes an impression cylinder, gripper transfer means for transferring a sheet from one impression cylinder to another, said means comprising a plurality of cylinders arranged in series between consecutive impression cylinders, and operatively connected to both of said impression cylinders, and a drive for each unit independent of the transfer means.
13. In a multicolor press having separate printing units each of which includes an impression cylinder, gripper transfer means for transferring a sheet from one impression cylinder to another, said means comprising a plurality of cylinders arranged in series between consecutive impression cylinders, and operatively connected to both of said impression cylinders, a drive member for said units, and driving connections between said member and each of said units independent of the transfer means.
14. In a multicolor press having separate printing units each of which includes an impression cylinder, gripper transfer means for transferring a sheet from one impression cylinder to another, said means comprising a plurality of cylinders arranged in series between consecutive impression cylinders, and operatively connected to both of said impression cylinders, and a drive for each unit independent of the transfer means, one of the cylinders of said transfer means having sheet registering connections.
15. In a multicolor press having separate printing units each of which includes an impression cylinder, gripper transfer means for transferring a sheet from one impression cylinder to another, said means comprising a plurality of cylinders arranged in series between consecutive impression cylinders, and operatively connected to both of said impression cylinders, a drive for each unit independent of the transfer means, one of the cylinders of said transfer means having sheet registering connections adapted to act alternately as the sheet is received by said cylinder and delivered therefrom.
16. In a multicolor press, two sheet carrying cylinders, means for driving said cylinders, a plurality of sheet transfer cylinders arranged in series between said driven cylinders, driving connections between each of said driven cylinders and the adjacent transfer cylinder, said driving connections comprising a gear with high teeth at one point, whereby it takes driving force alternately from the gears on opposite sides thereof.
17. In a rotary printing press, a plurality of multicylinder printing units, each unit comprising a sheet carrying cylinder, grippers on each of said sheet carrying cylinders, a driving member, separate driving connections between the driving member and two of the sheet carrying cylinders, gripper transfer means for transferring the sheet from the grippers on one of said driven cylinders to the grippers on the other, and means for driving the transfer means associated with both of said driven cylinders.
18. In a rotary multicolor press having separate printing units each of which includes an impression cylinder, gripper transfer means for transferring a sheet from one impression cylinder to another, said means having slack therein and comprising means for removing slack at the point of transfer of a sheet to the forward impression cylinder whereby the sheet is accurately registered upon that cylinder, and a drive to each unit independent of the sheet registering means.
19. In a rotary printing press, a plurality of interconnected sheet carrying members, sheet gripping means on said members, gripper transfer means for transferring sheets from the gripping means on one member to the gripping means on another member, and driving means for said members arranged to impart driving force to two of the members independently of each other.

CHARLES W. HARROLD. 65
